UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

MEANS FOR ADJUSTING THE MOLDS OF TYPOGRAPHICAL LINE-CASTING MACHINES.

966,227.

Specification of Letters Patent.

Patented Aug. 2, 1910.

Application filed May 28, 1910. Serial No. 563,967.

To all whom it may concern:

Be it known that I, CARL MUEHLEISEN, a citizen of the United States of America, residing at 88 Chausseestrasse, Berlin, N. 4, in the Empire of Germany, have invented new and useful Means for Adjusting the Molds of Typographical Line-Casting Machines, of which the following is a specification.

- 10 In the casting operation of a machine such as that known commercially under the trade mark "Linotype," the row of formative cavities in the composed line of matrices, fits up to the mold cavity in the mold block.
- 15 This mold cavity is the mold for the body of the cast line or type bar and the said row is the mold for the type on the edge of the cast type bar. The mold block consists of four members, the cap plate or upper wall, 20 the bottom plate or wall and two intermediate end liners. These four members are held firmly together, the cap plate above, the bottom plate below, and an end liner at each end of the mold cavity between them.
- 25 An increase in the thickness of the body of the cast type bar is, according to the present practice, provided for by adjusting the cap plate at a greater distance from the bottom plate which is always stationary, and changing 30 the end liners. So long as the body of the formative cavities and that of the mold cavity are the same, the line of type on the cast type bar always stands on it at an equal distance from both its sides. But if the cap
- 35 plate is adjusted for a thicker body than the formative cavities require, the line of type does not stand in the middle of the cast type bar but nearer to one side of it than to the other. If to these thicker type 40 bars, are added thinner type bars in the same column, the distances of the lines of type from each other will be irregular. To make these distances equal, it has been necessary to insert leads between the cast type bars, which insertion is troublesome and takes up time. The thickness of such a lead 45 is equal to a thick body less the portion that is occupied by the line of type. Thus it is the relative positions of the cap plate, row 50 of formative cavities and bottom plate, that decide the position of the line of type on the cast type bar.

The present invention provides for the above mentioned distances being equal, by 55 maintaining the longitudinal median line of

the mold cavity and the longitudinal median line of the row of formative cavities in the composed line coöperating with that mold, in the same plane, in spite of any change in the mold in respect of its body dimension, 60 the result being that the line of type will stand on the cast type bar at an equal distance from both its sides. The above mentioned maintenance is secured by making two of the three parts which decide the position of the line of type on the cast type 65 bar adjustable together.

Referring to the accompanying drawings:—Figure 1 is a section through five type bars cast in a mold of the construction 70 hitherto used: Fig. 2, a vertical section through the same five type bars after they have been leaded out: and Fig. 3 is a vertical section through five type bars having the same bodies and type as those of Figs. 1 75 and 2, but cast in a mold made according to the present invention. Fig. 4 is a longitudinal section; Fig. 5, a vertical section on the line 5—5 of Fig. 4 showing the mold adjusted for casting a thick type bar; and 80 Fig. 6, a similar section showing the mold adjusted for casting a thin type bar, together illustrating one embodiment of the invention. Fig. 7 is a longitudinal section on the crooked line 7—7 of Fig. 8, and Fig. 85 8 is a vertical section on the line 8—8 of Fig. 7, together illustrating another embodiment.

Referring to Figs. 1 and 2, 1, 1 are the lines of type on three bodies 2 of the same 90 size as the type; 3, 3 are the lines of type on two bodies 4 of a larger size than the said type 3; and 5, 5 are leads inserted between the type sides of each body 4 and the adjacent body 2.

In Fig. 3, the three lines of type 1 and bodies 2 and 4 are the same as in Figs. 1 and 2, but the two lines of type 3^a differ from the two lines 3 of the said figures, by being at an equal distance from both sides 100 of the respective body 4. Figs. 1 and 2 illustrate the practice obtaining at the date of the present invention. Fig. 3 illustrates the product of the latter, which is characterized by the lines of type 3^a being at equal 105 distances from both sides of the respective body 4 and by the consequent absence of the now unnecessary leads 5 of Fig. 2.

In the embodiment illustrated in Figs. 4 to 6, it is the cap plate and bottom plate of 110

the mold block, that are adjustable together, the row of formative cavities remaining stationary. 6 is the row of formative cavities; 7, the cap plate or upper member or wall of the mold; 8, the bottom plate or lower member or wall of the mold; 9, the mold cavity; 10, an upstanding piece at each end of the bottom plate 8, recessed to receive a spiral spring 11 (and acting also as the respective end liner); 12, a stud depending from each end of the cap plate 7 and entering the respective spring 11 to serve as a guide for the same; 13, a wedge adjustable lengthwise in either direction between the cap plate 7 and a stationary abutment 15; 14, a similar wedge adjustable lengthwise with the wedge 13, between the bottom plate 8 and a stationary abutment 16; 17, a cross head connecting the adjacent ends of both wedges; 18, a screw engaging in a screw-threaded hole in the cross head 17 and also in the adjacent piece 10 on the bottom plate 8, by a collar 19 or its equivalent, in such a way that the turning of the screw 18 will move both wedges 13 and 14 together in respect of both time, direction and distance, provision being made, as for example by sufficiently extending in a vertical direction, the grooves 20 with which the collar 19 engages, to admit of the bottom plate 8 moving in the vertical direction independently of the screw 18. This motion of the wedges will move the cap plate 7 and the bottom plate 8 through equal distances toward 1 or away from the median line 27 according to the direction in which the said screw 18 is turned. 21 is one of the matrices of the composed line and 22 is a ridge fast on the matrix support 23 and holding the cavities 6 symmetrical with the said line 27 by being embraced by corresponding notches in the front edges of the matrices.

In the embodiment illustrated in Figs. 7 and 8, it is the cap plate 7 and the row of formative cavities 6 that are adjustable together, the bottom plate 8 remaining stationary. The adjustability of the row 6 involves the movement of the median line 27 up or down. As the movements of both row 6 and cap plate 7 are in the same direction, the movement of the said line 27 will be half that of the cap plate 7, and as the row 6 must always be symmetrical with reference to the said line, their movements must be equal. To meet this requirement, the cross head or lever 17 turns on a pivot 24 carried by the bottom plate 8, and has its ends pivotally connected to the ends of the respective wedges 13, 14, as by slots 25 embracing studs 26; the wedges 13, 14 move in opposite directions; the wedge 14 has half the obliquity of the wedge 13 (or, as an equivalent, the bottom arm of the lever 17 is half the effective length of the top arm); the matrix support 23 is movable vertically, and

the wedge 14 works between it and the abutment 28. The pivoted lever 17 may be moved directly by hand instead of by the screw 18 and its adjuncts of Figs. 4 to 6. The wedges 13, 14 may be replaced by any suitable equivalent such as screws or eccentrics.

Having described my invention, what I claim and desire to secure by Letters Patent is:

1. In a typographical line-casting machine, the combination with two mold members of a matrix support symmetrically disposed as to the median line of the mold, and connected adjusting means to move the said parts relatively to each other so as to vary the size of the mold and yet preserve their symmetrical relations as to its median line. 80

2. In a typographical line-casting machine, the combination with two mold members forming the opposite walls of the mold cavity, of a matrix support symmetrically disposed as to the median line of the mold, and connected adjusting means to move the said parts relatively to each other so as to vary the width of the mold cavity for changes of body and yet preserve their symmetrical relations as to its median line. 85

3. In a typographical line-casting machine, the combination with two mold members each adjustable relatively to the other for changes of body, of two wedges movable independently of the members and each adapted to adjust one of the said members, and means operatively connected with both of the wedges by which they can be adjusted simultaneously. 95

4. In a typographical line-casting machine, the combination with two mold members each adjustable relatively to the other for changes of body, of springs tending to move the said members relatively to each other, two wedges movable independently of the said members and each adapted to move one of them in the direction opposite to that due to the respective spring, and means operatively connected with both of the wedges by which they can be adjusted simultaneously. 105

5. In a typographical line-casting machine, the combination of two mold members each adjustable relatively to the other for changes of body, springs tending to move the said members apart, two wedges movable independently of the said members and adapted to move them toward each other, means rigidly connecting the two wedges together, and a screw engaging the said means and adapted to move both of the wedges simultaneously. 115

6. A mold for a typographical line-casting machine comprising, in combination, two members forming opposite walls of the mold cavity, springs tending to move them apart and adjusting wedges to move them to. 125

gether, whereby said members are moved simultaneously and equally toward and from the median line of said cavity.

7. A mold for a typographical line-casting machine comprising, in combination, two members forming opposite walls of the mold cavity, and adjusting means therefor, whereby said members are moved simultaneously and equally toward and from the median line of said cavity.

8. In a mold for a typographical machine having an elongated mold slot or cavity, end walls for said cavity at a fixed distance apart to determine the length of the slug cast therein, side walls for the cavity to determine the thickness of the slug, and adjusting means therefor, whereby said walls are simultaneously and equally moved in opposite directions without disturbing the end walls.

9. In a slotted mold for typographical machines, two parallel members between which the mold cavity exists, means for

preventing movement of said members endwise, and a single connected means for adjusting said members simultaneously and equally toward and from each other.

10. In a line-casting machine wherein a composed line of matrices co-operates with a slotted mold, means for holding the matrices against end motion and in operative position, in combination with a slotted mold comprising two members between which the mold slot exists, and adjusting means for said members whereby they are simultaneously and equally moved toward and from the median line; whereby given characters may be produced centrally on slugs of greater or less thickness as demanded.

In witness whereof I have hereunto set my hand in the presence of two witnesses.

CARL MUEHLEISEN.
